UNITED STATES PATENT OFFICE

WILLARD F. RICHARDS, OF DEPEW, NEW YORK, ASSIGNOR TO THE GOULD COUPLER COMPANY, OF NEW YORK, N. Y., A CORPORATION OF MARYLAND

COUPLER

Application filed May 6, 1926. Serial No. 107,150.

This invention relates to car couplers and, more especially, to couplers having a vertically moving gravity actuated lock.

This invention, generally considered, has for its principal object the production of a coupler having positive control of the locking block at all stages of its operation both with respect to position and operation.

More particularly it has for an object the production of a coupler in which the coupler head and the locking block are provided with interengaging portions to retain the block securely in locked position and to prevent the block from becoming displaced in service.

Another object is to provide means within the head to direct the locking block against the rear wall and a side wall so as to hold the block securely in locked position.

A further object of this invention is to provide a coupler in which the locking block and the locking face of the tail of the knuckle cooperate to retain the block in locked position and prevent vertical displacement commonly called creeping.

A valuable feature of my invention is the employment of a locking block comprising two interlocking segments hinged together, one of which performs primarily the function of a guide, the other of which performs primarily the function of a lock. The latter is also adapted under the action of the knuckle opener to positively engage a ledge in the locking wall of the head to afford a lock-set position. This improved form of locking block further permits the reduction in size and weight of the coupler head with no loss in strength.

Throughout the specification and the drawings, like parts are designated by like reference characters.

In the accompanying drawings forming part of the specification:

Figure 1 is a view in vertical longitudinal section of a coupler head embodying a preferred form of the invention and showing the parts in locked relation.

Figure 2, is a view partially in plan and partially in horizontal section showing especially the locking block, retaining and guiding ribs.

Figure 3 is a transverse vertical sectional view of the head, taken in front of the locking block on the line 3—3 of Figure 2, showing the parts in locked position.

Figure 4 is a similar view showing the locking block and related parts in lock-set position.

Figure 5 is a perspective view of the two segments of the improved locking block.

Figure 6 is a side elevation of the two segments of the locking block.

Considering the drawings in greater detail, it will be noted that a coupler of the A. R. A. type is shown having a head 1, a guard arm 1^a, a coupler shank 2 and a knuckle 3 pivotally connected to the head by means of a knuckle pin 3^a. Shoulders are provided on the knuckle at 3^b and on the head at 1^b to receive buffing strains. The tail 4 of the knuckle extends into the head for engagement with the lock through the means of an undercut locking face 5, the function of which will be described later. The tail is also provided with the usual lateral extension 4^a adapted to engage a portion of the head and receive part of the draft strains. A knuckle opener 6 of a bell crank lever type is pivoted horizontally within the head and so proportioned that the lower part will tend to remain in contact with the knuckle tail under the action of gravity. The knuckle opener is also adapted to be actuated by the locking block 7 as hereinafter described.

Referring to Figures 5 and 6, it will be seen that the locking device 7 is preferably formed of the two interlocking segments or blocks 7^a and 7^b connected by the hinge pin 8, forming a compact unit of a height but slightly more than the height of the tail 4 thereby permitting the use of a head of minimum height. This locking block is adapted to operate in a vertical well of generally rectangular cross section formed by the locking wall 1^d, the rear inner wall 1^e and an inner side wall 1^f on the knuckle side of the head. The segment 7^a or guide block is shown as provided with an eye 9 for top operating means, although bottom operating means may be provided, if desired, to meet the requirements of certain types of car

construction. Segment 7^a is also provided with a projection or rib 10 adapted to operate in the recess behind the intermediate guide ribs 11 extending from the inner side wall 1^a to assist in guiding the locking block in its vertical motion. This side projection of the segment 7^a may be extended to form also a bottom projection 12 adapted to cooperate with the wedge shaped projection 13 of the floor of the head, to seat the block in locked position against the rear inner wall 1^a of the head. The projection 10 may be bevelled at the corner 14 to cooperate with the inclined portion of the head 15 to seat the lock against the inner side of the locking wall 1^a. The wedging action of inclined faces 13 and 15 not only holds the block securely in locked position but operates to take up the necessary clearance between operating parts, required by economical manufacturing. The engaging portions of the locking block at 10 with the guide rib 11 and the bottom projection 12, with the floor projection 13, further operate to prevent the block from swinging out beyond the face of the coupler and interfering with the lock-setting function, or becoming displaced by the impact of two couplers coming together with both knuckles closed as frequently occurs in switching. The floor projection 13 also acts to support the block 7 at sufficient height above the floor of the head to provide space to accommodate cinders and other particles which might otherwise interfere with the proper seating of the block in lock position.

The segment 7^b or locking block of the locking means 7 is preferably pivoted to the segment 7^a off center so that the action of gravity tends to swing the segment 7^b against the locking wall 1^a. In addition the segment 7^b may be provided with a seat 16 to receive the upper end of the knuckle opener 6 which, on the lifting of the block, operates to swing the segment 7^b against the locking wall 1^a and effect the positive engagement of the corner 17 with the lock-set ledge 18 irrespective of the action of gravity, thereby overcoming a difficulty not infrequently encountered in couplers employing gravity solely to effect the lock-set position. When the locking block is further lifted, the knuckle opener is actuated to move the tail towards the guard arm side of the head and to open the knuckle in the usual manner.

The locking block 7 and the tail 4 are so arranged that on the opening of the knuckle the tail will lift the block from the lock-set ledge 18 and on the closing of the knuckle, as in coupling, the tail will drag the locking block away from the lock-set ledge and support the block until disengaged, whereon the lock will drop into its seat in locked position. Referring to Figure 3, it will be noted that the segment 7^b is wedge shaped with an inclined locking face 19 adapted to

cooperate with the undercut locking face 5 of the knuckle tail so that the movement of the knuckle while the car is in motion will constantly tend to reseat the locking block and prevent creeping. The guide ribs 11 are provided with a recess 20 adapted to provide additional space for the hook of the lifting means 21.

The improvements embodied in this invention as described have proven their value in actual manufacture and use and the resulting coupler, is compact, strong and positive in action. The parts are relatively large, simple in form and easy to make. The compensating action of the inclined faces 13 and 15 ensures proper seating of the block at all times and reduces materially the motion of the locking block within the head with a corresponding material reduction in wear.

Having now described my invention, what I claim is:

1. In a car coupler, the combination with a draw head having a pivoted knuckle, of locking means therefor comprising a locking block and a guide block pivotally connected, means actuated by said locking block for opening said knuckle, cooperating ribs on said head and guide block for maintaining said locking means from movement longitudinally of said head and cooperating means on said knuckle and said locking block for normally maintaining said locking means against vertical creeping.

2. In a car coupler, the combination with a draw head having a pivoted knuckle, of locking means therefor comprising a locking block and a guide block pivotally connected, means actuated by said locking block for opening said knuckle, cooperating means on said head and guide block for maintaining said locking means from movement longitudinally of said head and cooperating wedging means on said head and said guide block to direct said locking means against the rear inner wall and a side inner wall of said head.

3. In a car coupler, the combination with a draw head having a pivoted knuckle, of locking means therefor comprising a locking block and a guide block pivotally connected, means actuated by said locking block for opening said knuckle, cooperating inclined means on said head and said guide block to direct said locking means against the rear inner wall and a side inner wall of said head and cooperating means on said knuckle and said locking block for normally maintaining said locking means against vertical creeping.

4. In a car coupler, the combination with a draw head having a pivoted knuckle, of locking means therefor comprising a locking block and guide block pivotally connected, cooperating means on said head and guide block for maintaining said locking means from movement longitudinally of said head, cooperating means on said head and guide

block to direct said locking means against the rear inner wall and an inner side wall and cooperating means on said head and said locking block to support said locking means in a lock-set position.

5. In a car coupler, the combination with a draw head having a pivoted knuckle, of locking means therefor comprising a guiding block and a locking block pivotally connected for movement together as a unit, a knuckle opener actuated by said locking block for opening said knuckle, said locking block being adapted to swing sideways under the action of gravity and the thrust of said knuckle 10 opener to engage a ledge in the locking wall of said head for supporting said locking means in a lock-set position.

6. In a car coupler, the combination with a draw head having a pivoted knuckle, of locking means therefor comprising a guiding block and a locking block pivotally connected for simultaneous movement, a knuckle opener actuated by said locking block for opening said knuckle, said locking block being adapted to swing sideways under the action of gravity and auxiliary means to effect engagement with a ledge in the locking wall of said head for supporting said locking means in a lock-set position.

7. In a car coupler, the combination with a draw head having a pivoted knuckle and a horizontally pivoted knuckle opener, of locking means therefor, said means comprising two segments pivoted together, one of the segments being provided with a projection for cooperating with a portion within the head for guiding said means in its vertical movement, said projection being adapted to engage the lower end of said portion and a projection from the floor of the head to restrain the locking means from swinging out of position, one of said segments being adapted to swing sideways under the action of gravity and the thrust of the upper end of said knuckle opener to engage a ledge in the locking wall to support said locking means in a lock-set position.

8. In a car coupler, the combination with a draw head having a pivoted knuckle and a horizontally pivoted knuckle opener, of locking means therefor, said means comprising two segments pivoted together, one of the segments being provided with a projection for cooperating with a portion within the head for guiding said means in its vertical movement, said projection being also adapted to engage a projection from the floor of the head to restrain the locking means from swinging out of position, one of said segments being adapted to swing sideways under the action of gravity and the thrust of the upper end of said knuckle opener to engage a ledge in the locking wall to support said locking means in a lock-set position.

9. In a car coupler, the combination with a draw head having a pivoted knuckle, of locking device therefor, cooperating means on said head and said device for maintaining said locking device from movement longitudinally of said head, cooperating wedging means on said head and said locking device to direct the locking device against the inner rear wall and an inner side wall of said head and cooperating means on said knuckle and the locking device for normally maintaining said device against vertical creeping.

10. In a car coupler, the combination with a draw head having a pivoted knuckle and a horizontally pivoted knuckle opener, of locking means therefor, said means being guided for vertical movement by an inner portion of the head extending towards the locking wall, said means when raised being adapted under the action of the upper end of the knuckle opener to engage a ledge in the locking wall to retain said means in a lock-set position, said locking means being formed to cooperate with said knuckle with a wedging action to retain said locking means in position against vertical creeping.

11. In a car coupler, the combination with a draw head having a pivoted knuckle, of locking means therefor, said head being provided with an inclined portion adapted to direct said locking means against the locking wall in locked position, said locking means being provided with a wedge-shaped portion adapted to coact with an inclined face of said knuckle to prevent vertical creeping.

12. In a car coupler, the combination with a draw head having a pivoted knuckle, of locking means therefor, the floor of said head being provided with a projection adapted to engage a corresponding projection on the locking means and retain it in proper position, said locking means being provided with a wedge-shaped portion adapted to coact with inclined faces of said knuckle to prevent vertical creeping.

13. In a car coupler, the combination with a draw head having a pivoted knuckle, of locking means therefor, said means being restrained against outward movement in its lowest position by a portion thereof engaging an extension from the knuckle side of the head and another portion engaging a projection from the floor of said head, said means being restrained against vertical movement in locked position by a wedge-shaped portion engaging an inclined face of the knuckle on one side and the locking wall on the other.

14. In a car coupler, the combination with a draw head having a pivoted knuckle, of locking means therefor, said means being adapted to move in a vertical recess within the head, being guided in said motion by portions coacting with portions of the head for maintaining said locking means from move-

ment longitudinally of said head, and other portions within the head adapted to direct said locking means in its lowest position against the rear wall and the locking wall of said head.

15. In a car coupler, the combination with a draw head having a pivoted knuckle, of locking means therefor, said means being restrained against outward movement in locked position by a portion thereof engaging an extension from the knuckle side of the head and another portion engaging a projection from the floor of said head, said projection being adapted to support said means and provide space thereunder for accumulation of cinders and the like which might interfere with the action of said locking means.

16. In a car coupler, the combination of a draw head having a knuckle and a knuckle opener pivoted thereto, of locking means therefor, said means being guided in its vertical motion by an inner projection on the head extending towards a wall thereof and disposed intermediate the front and rear faces of the locking means, said means when raised being adapted to actuate said knuckle opener to open said knuckle, being adapted under the action of gravity to engage a shoulder in the locking wall to retain said means in lock-set position, and formed to cooperate with said knuckle with a wedging action to retain said locking means in a position against creeping.

17. In combination, a coupler head, a swinging knuckle, a locking device for said knuckle, and an extension on the bottom of said device adapted to engage the rear face of a lug on the bottom of the head, said face sloping downwardly and rearwardly for guiding said locking device against the rear wall of the head, when said device is in locked position, for preventing longitudinal displacement thereof.

18. In combination, a coupler head, a swinging knuckle, a locking device for said knuckle comprising a locking block and a guide block pivotally connected, said locking block being adapted for positioning between the tail of said knuckle and the guard arm side wall of the head, said guide block being formed with a downward extension, the corner of said extension, away from said guard arm side wall, being bevelled and engaging a correspondingly bevelled face on the head for causing the guide block and locking block to move toward the guard arm side wall for taking up lost motion.

19. In combination, a coupler head, a swinging knuckle, locking means for said knuckle comprising a locking block and a guide block pivotally connected so that the locking block is swingable laterally to lock-set position with respect to a ledge on a side wall of the head, said guide block being formed with a laterally projecting rib, and

a corresponding rib on the head extending forwardly of said rib for limiting longitudinal movement of said guide block guiding the same in vertical movement, and preventing longitudinal swinging of the locking block and interference with the locksetting function.

20. In combination, a coupler head, a swinging knuckle, a locking device for said knuckle comprising a locking block and a guide block pivotally connected, and a knuckle opener movably mounted with respect to the head and engaged by said locking block upon upright movement thereof for opening said knuckle, said engagement effecting a positive movement of said locking block to lock set position.

In testimony whereof I affix my signature.

WILLARD F. RICHARDS.
